UNITED STATES PATENT OFFICE.

JOSEPH BONHOMME, OF NICE, FRANCE.

WIRELESS APPARATUS FOR PREVENTING COLLISIONS.

1,073,088.

Specification of Letters Patent. Patented Sept. 16, 1913.

Application filed July 14, 1910. Serial No. 572,002.

To all whom it may concern:

Be it known that I, JOSEPH BONHOMME, a citizen of the Republic of France, residing at 3 Rue Pertinax, Nice, Alpes Maritimes, in the Republic of France, engineer, have invented certain new and useful Improvements in Wireless Apparatus for Preventing Collisions, of which the following is a specification.

10 The present invention relates to an electric installation intended to avoid collisions on the sea and also the stranding of ships in places regarded as dangerous for navigation.

This installation comprises essentially 15 sources of electricity and wireless telegraphy transmitting and receiving apparatus of a conventional form and very short range as well as ringing devices, this plant being placed on ships or boats which will be called 20 "movable stations", and also at places regarded as dangerous to navigation, such as light-houses, entrances to ports, rocks, etc., such places being called "fixed stations." Each installation or station also comprises 25 apparatus combined with the aforesaid apparatus and serving to automatically close the electric circuits of the corresponding ringing devices when two or more ships or a movable station and a fixed station are situated for the moment in the sphere of action 30 of the Hertzian waves emitted by each of them. To each installation there is also added an ordinary telegraph or telephone apparatus permitting ships to communicate 35 either with each other or with a light-house or a port when they are in the sphere of the oscillatory waves emitted by each of them.

The particular arrangements of this invention are for the purpose of creating 40 around each ship or dangerous fixed spot a circular zone called a "protection zone," of which the said ship or danger spot forms the center and in which either another ship, or a fixed station provided with the aforesaid 45 apparatus is automatically signaled by loud ringings on the ship or ships as well as at the station at the dangerous place, that is to say at both the sources of danger, such ringings being adapted to be stopped temporarily 50 for the purpose of allowing telegraphic or telephonic signals to be exchanged between the interested parties.

So far as possible each protection zone should be of the same extent for all the ships 55 or stations; such zone is conventional, that is it may be of any extent considered desirable

for proper navigation, of a radius, for instance, of about one, two, five or ten kilometers, etc., around the ship or fixed station. Two ships, or a ship and a fixed station, 60 only render their ringing device operative respectively when they are at a distance not exceeding a radius of the zone from each other.

According to this invention, each ship or 65 each fixed station comprises a switch apparatus operating continuously and having the effect of connecting alternately with the surrounding ether, the transmission apparatus, and the wireless telegraphy receiving apparatus carried by each ship or each fixed station, the earthing wires being continuously 70 immersed in the water.

Should, at any moment, two ships or a 75 ship and a fixed station find themselves in their protection zones, a current passes through their switch apparatus and the ringing devices of the said ships or fixed stations ring loudly at once and continue to ring so long as the ships or the fixed stations are 80 located in the common part of their protection zones. Should the two stations move out of such common part or should their protection zones no longer overlap their alarm bells will stop automatically. The 85 captains of the ships are thus automatically warned of the presence of an obstruction in the area in which their ships are sailing and of the disappearance of such obstruction. In order to secure such result all that need 90 be done is to avoid absolute synchronism between the periods of emission and reception of the two ships or of the fixed station the protection zones of which overlap. Such 95 synchronism can be avoided with certainty by the means hereinafter described and shown.

In order to start the alarm signals as soon as the two ships or a fixed station and a ship are situated in the same zone of protection, each ship or in each fixed station there is provided a wireless telegraphy transmission apparatus, the coil of which is so adjusted as to produce a similar or nearly similar spark in each apparatus and a wireless telegraphy apparatus receiving apparatus; this latter apparatus is combined with the alarm signals; these two transmission and reception apparatus being controlled by the switch apparatus hereinbefore mentioned. It is to be observed, however, that if the fixed stations consist of apparatuses 100 105 110

identical with those of the movable stations, the wireless telegraphy reception apparatus may be dispensed with in said fixed stations, without inconvenience, and further to advantage in certain cases leaving only the transmission apparatus for the purpose of emitting continuously and without interruption Hertzian waves in its protective zone.

One embodiment of this invention is shown by way of example in the accompanying drawings, in which:

Figure 1 is a diagrammatic view of the apparatus; the full lines correspond to the period of emission of oscillatory waves, the receiving apparatus being inoperative as no other station is in their protection zone to influence the same. The dotted lines show the positions which correspond to the case where the receiving apparatus has just been influenced by another apparatus, the transmitting apparatus being out of action for the moment. Fig. 2 shows one way of arranging the controlling relay of the system as a whole when it is under the influence of another apparatus; and Fig. 3 shows another way of arranging the controlling relay when under the influence of another apparatus.

In Fig. 1, the circuit 1, 2, 3, 4 comprising the batteries 1 and the coil 2 give to the radiators 5 and 6 the spark necessary to transmit the Hertzian waves through space by means of the wire 7 connected with the antenna 8.

4 is a switch and 9 a Morse key for testing the apparatus or for sending a message. Such transmission station may be of any suitable system. The electro-magnet 10 and its armature lever A automatically control such emission apparatus at 3. The circuit 11, 12, 13 actuates the relay 13 through the batteries 11.

12 is the radio-conductor (that shown in the drawings is of the "filings" type). Such circuit and such apparatus, which constitute a wireless telegraphy receiving station, may be of any suitable system. However, to avoid the reception of waves not emanating from another similar apparatus, it must be syntonized with the transmitting apparatus by suitable means. Such receiving apparatus is connected with the antenna 8 by the contact 14 and the switch 15.

The whole of the receiving station is in closed in a casing 16 for protecting the receiving apparatus from oscillatory waves which may be either injurious, extraneous, or parasitic and which flow to the sea through 17; the wires leading from the casing pass through insulators 18. Any other suitable form of receiving apparatus may, however, be adopted.

The ground wire of the receiving circuit may be arranged in the usual way, whether what is termed the "direct" method of

reception or the "shunt" method be employed.

19 is a battery of cells, 20 is an electro-magnet actuating the lever armature B; 10 designates an electro-magnet actuating the lever armature A.

The operation is as follows:—21 is a motor, such as a clock-work, or a small electric motor, which actuates in a continuous manner the cam wheel 22; the latter constitutes the switch which controls the whole of the system when not subjected to external influence and which will hereinafter be fully described. Assuming that the "protection zone" selected is of a radius of 10 kilometers and that, for the moment, no other similar station is situated in the same zone; the apparatus will operate as follows: When one of the cams of the wheel 22 lifts the switch 23, no current will pass into the electro-magnet 10; the transmission apparatus will not operate, its circuit being interrupted at 3, as shown in dotted lines. When, on the contrary, the wheel 22 allows the switch 23 to fall, the circuit 19, 10, 23, 19 will be closed, the electro-magnet 10 will attract the armature A which, through 14, will insulate the receiving apparatus from the antenna and then through the contact 3 actuate the transmitting apparatus, as shown in firm lines in Fig. 1.

As will be seen, through the switch 23, the cam wheel 22 controls the whole of the system in connecting the antenna 8 alternately with the receiving apparatus and with the transmitting apparatus, the latter being thus automatically started. To balance the circuits, the coil 25, equivalent to the coil 26, is provided. Let us now assume that during one of the receiving periods controlled by the wheel 22, another movable or fixed station, provided with a similar apparatus, sends waves which actuate the wireless telegraphy circuit 11, 12, 13. Immediately the coil 13 attracts the armature 27; the circuit 19, 25, 20, 19 is closed and the armature B becomes attracted to the coil 20. At the beginning of its stroke the said armature B closes the circuit 19, 29, 28, 19, which starts the alarm bell 29. Again at the beginning of its stroke, the armature B breaks the circuit 19, 10, 23, 19; the distributing action of the cam wheel 22 is therefore stopped so long as the armature B remains completely or partially in contact with the coil. Before the end of its stroke, however, the armature B closes another circuit 19, 26, 30, 20, 19 which only begins to operate when the armature B is completely in contact, which constitutes an important feature; and through the coil 26 this latter circuit actuates the striking switch 31 which serves to destroy coherence in the filings tube 12. So long as 12 receives the Hertzian waves coming from the outside, the armature B will

remain in contact with the electro-magnet 20 and the coherer will be struck by the striker 31 in the usual manner, but as soon as these waves no longer exert their influence on the coherer 12, the circuits will be broken at 27, and the armature B will be returned by the spring 32; but the ratchet wheel 33 will then intervene, such wheel receiving from the motor 21 a slow and regular rotary motion.

10 The armature B has a pawl 34 which becomes engaged in the teeth of the ratchet wheel 33 and which is so pivoted that the armature B is enabled to move up suddenly and to the full extent under the influence of

15 the coil 20, but it can only move down again very slowly in following the movement of the wheel 33 which retains it by means of the pawl 34. This device is only given by way of example; two other devices giving

20 the same results and shown in Figs. 2 and 3 will be described hereinafter.

The temporary retention of the armature B is to enable it during its descent to distribute periods of emission through 35 and 25 of reception, which periods are fixed and equal for all similar apparatus, the circuit controlled by the wheel 22 and the switch 23 being still out of action. Such distribution made by the armature B on the contact 35 is for the purpose of obtaining a continuous ringing at 29 so long as two stations, movable or fixed, are located in the same danger zone, (for instance at least ten kilometers one from the other) irrespective of the time 35 they remain in such zone. By way of example, the shortest reception period controlled by the cam wheel 22 may be fixed at more than 10 seconds in all the similar apparatus which may exist in the world. Let us 40 now suppose two ships X and Z are provided with the present apparatus; as soon as they are less than ten kilometers from each other, as will be hereinafter explained, one of the two ships, say the ship Z, through its switch 22, will automatically send waves which will be received by the apparatus of the ship X. Immediately the bar B of the apparatus of X will be attracted or in full contact and will remain so until the ship Z 45 by means of its commutator 22, ceases to send Hertzian waves and, through 22, has been automatically rendered receptive. At this moment, the bar B of X, released by the electro-magnet 20, will move down very 50 slowly, being retained by the ratchet wheel 33; when released B will descend from its stopping point 36 to 35 where it will establish a contact giving an emission; for efficient operation B should move from 36 to 35 in much less time than that required for the shortest reception period of 22; let us assume that the bar B will take five seconds to move from 36 to 35. As the apparatus of Z is rendered receptive by 22, since the bar 55 B of X was released by 20, and as the short-

est reception period of the commutator 22 of Z is 10 seconds, it follows that the bar B of Z will be armed or in contact as soon as the bar B of X has reached 35, that is to say five seconds after the last emission from Z. 70 If we assume that the bar B of X during its descent will insure 15 seconds of contact on 35 and consequently 15 seconds of emission of waves, the bar B of Z will remain armed or in full contact during the whole of this 75 time. As soon as the bar B of X has left the contact 35, it will continue to move down in space, that is to say in the reception phase, during 15 seconds before coming to rest again on 37. But, during these 15 seconds of descent of the bar B of X in the reception phase the bar B of Z will also effect its first descent in the reception phase, but such descent will only last five seconds so that it follows that the bar B of X will 80 be attracted or in full contact again as soon as the bar B of Z has reached the contact 35. The bar B of X will remain in contact during the 15 seconds of emission from the bar B of Z, then after a descent of five seconds, 85 the bar B of X will arm in its turn the bar B of Z which is then effecting its second reception descent of 15 seconds, and so on so long as the two ships are less than ten kilometers one from the other and there is 90 no fear of failure, the emission and reception currents of each ship succeeding each other in consequence automatically and of themselves with a large margin of operation to avoid any cumulative action. During all 95 these exchanges the alarm bells 29 of each ship will continue to ring.

It will be understood that the times of 5, 10 and 15 seconds given above may be changed, as they are only given as indication. It will also be understood that absolute synchronism between the periods of emission and of reception of the apparatus carried by the two ships, should it occur accidentally, might disturb such apparatus. 100 While such a case seems unlikely, any such synchronism can be safely avoided not only in adjusting the motors 21 of the several apparatus at slightly different speeds, but also by giving to the projections of the 105 wheels 22 a series of slightly different lengths for each ship, according to an agreed code. 110

According to requirements and circumstances, each circuit may be given its unity 120 and independence by providing as many series of batteries as there are circuits, instead of leaving all the circuits to be actuated by the battery 19, as shown in Fig. 1. In this case, as will be understood, it will 125 be necessary to provide on each circuit a small relay for the purpose of actuating the circuit which it is to control.

In Fig. 1, 15 designates a switch which, after having previously cut out the trans- 130

mitting circuit at 4 and the receiving circuit at 39, enables the Hertzian waves, coming from 8, to be directed through 38 to an ordinary wireless telegraphy receiving device not shown in the drawings, in order to receive despatches or telephone messages. In this case, the Morse key 9 serves for the transmission of telegrams; if the telephone is employed all that need be done is to insert a suitable apparatus in the transmitting circuit. The bar B and its accessories, the ratchet wheel 33 and the contact system 35 are shown diagrammatically; in practice, any other system may be employed which renders the same services, as shown for instance in Figs. 2 and 3.

In Fig. 2, the contact 35 is secured by friction. The bar B has at each of its ends a toothed arc concentric with the pivot of the bar B. The arc 41 actuates the toothed wheel 42, which is rigid with a wheel 43 carrying a cam 44. The said wheel 43 normally bears, by means of a stop piece 45, upon the contact 37 in such a manner as to limit the movement of the bar B when retracted by the spring 32. 44 and 45 are insulated and are permanently in electric communication with each other and with the circuit 40, Fig. 1. When the electro-magnet 20 attracts the bar B the latter in tilting causes the wheel 43 to rotate; the latter in rotating breaks the circuit at 37 and its cam 44 in passing comes against the slightly flexible contact 35, but without establishing any electric contact with the same as beneath the blade 35 another small blade 46 of insulating material is riveted and during the forward movement takes the friction of the cam 44. On the bar B moving down, the cam 44 rotating in the opposite direction then strikes the conducting blade 35 directly. The cam 44 is so arranged that on its return the predetermined reception and emission periods are insured. The toothed arc 42 actuates the tooth 47 rigidly connected with the ratchet wheel 33. The ordinary wheel 48, to which a slow and continuous rotary movement is imparted by the motor 21, is, as was explained for the ratchet wheel 33 in Fig. 1, independent of said wheel 33; it carries a pawl 34 held in mesh with the teeth of 33 by a spring 49 so that the bar B is able to move up suddenly when attracted by the electro-magnet 20, but can only move down slowly again when retracted by the spring 32 in following the movement of the wheel 48. In order to simplify the members and the friction, the members 41 and 42 may be dispensed with, and the cam wheel 43 and all the members attached thereto may be carried on the shaft of 47 and of 33.

In Fig. 3, the contact 35 is insured by a rod dipping into mercury. In the depression of the bar B by the ratchet wheel the

retaining device is identical with that shown in Fig. 2, but the other end of the bar is bare and terminates in a point forming the electric continuation of the circuit 40. In the said device, when the bar B is attracted by the electro-magnet 20, the end of the bar comes against and raises the blade 50 which pivots at 51 and then falls down again onto its seat after the bar has passed. When on the contrary the latter is released by the electromagnet 20, it moves down slowly at first, (say during 5 seconds) in space, that is to say in leaving the apparatus at "reception," then it comes against the blade 50 in carrying the same along with it and in causing the point 52 to dip during 15 seconds in the mercury 35, then again, after the lapse of the said 15 seconds, the bar B releases the blade 50, the emission is finished, and the bar B continues to insure in its descent a reception period of 15 seconds before again coming into contact with the contact 37. The lever 53 pivots around the shaft 54. 55 is its adjustable counter-spring and 56 is its abutment which is also adjustable. The serial antenna may also be replaced by a submarine antenna; in this case the water is employed as the means for transmitting the Hertzian waves.

I claim as my invention:

1. In a wireless apparatus for the prevention of collisions, a series of stations each comprising the combination of a transmitter, a receiver, an antenna, a circuit comprising a battery, an electro-magnet and a switch, means actuated by the said electromagnet to place said transmitter and receiver alternately in communication with the antenna, means mechanically actuated to open and close said switch continuously at predetermined intervals, a shunt on a part of the circuit which comprises the said switch, a swinging member, a relay controlled by the receiver in the field of influence of another station and actuating said swinging member to alternately cut out and close said shunt and part of the said circuit, whereby the alternations of emission and reception are controlled by the action of the said means mechanically actuated as long as the stations are outside the field of influence, and by the oscillations of swinging member when the stations are within said field of influence.

2. In a wireless apparatus to prevent collisions, a series of stations each comprising the combination of a transmitter, a receiver, an antenna, a circuit comprising a battery, and electro-magnet and a switch, means actuated by the said electro-magnet to put the transmitter and receiver alternately in communication with the antenna, means mechanically actuated to open and close the said switch continuously at predetermined intervals, a shunt on a part of the said circuit

which comprises the said switch, a swinging member adapted to cut out and close alternately the said shunt, and the said part of the said circuit, a relay controlled by the 5 said receiver in the field of influence of another station and actuating the said swinging member, and retarding means adapted to make the oscillation of the said swing member last a determined amount of time 10 in the direction in which it returns to close the part of the circuit comprising the switch.

3. A wireless apparatus for preventing collisions consisting of a series of stations 15 each comprising an antenna, an emitter, a receiver, and means for alternately con-

necting the antenna with said emitter and receiver; combined with a circuit controlling said means and including a source of electricity, an alternately moving switch, 20 a distributing relay, and a signal device; and a second circuit controlling said relay and itself controlled by the waves received from a companion station.

In testimony, that I claim the foregoing 25 as my invention I have signed my name in presence of two subscribing witnesses.

JOSEPH BONHOMME.
